UNITED STATES PATENT OFFICE.

FRANK S. SAXTON, OF BLISSFIELD, MICHIGAN.

CLOTHES HANGER.

Application filed July 5, 1928. Serial No. 290,398.

My invention has for its object to provide a clothes hanger that is so constructed that it may be readily secured in position on an edge of an object and so that its parts will be elastically pressed against the object to hold it in position. The invention particularly provides a clothes hook that may be readily supported by hooking it over the edge of the glass of an automobile window or door so that clothes, such as coats and hats, may be supported thereby. The hook embodying my invention is so formed that it may easily be carried in a pocket or readily placed in position on the upper edge of a window for the support of garments.

The invention may be contained in clothes hooks or hangers that vary in their details and, to illustrate a practical application of the invention, I have selected a hook containing the invention and shall describe it hereinafter. The clothes hanger selected is shown in the accompanying drawings.

Fig. 1 of the drawings illustrates the interior of an automobile and shows two of the hangers located in position for supporting hats and coats. Fig. 2 illustrates a view of a cross section of the hanger located in position on the upper edge of the glass of an automobile window. Fig. 3 is a perspective view of the hanger.

The clothes hanger is formed of an elastic metal strip oblong in its cross section, to form relatively wide lateral surfaces. The strip is bent at different points in order to form three hooks from the strip and so that the wide surfaces of the strip constitute the supporting surface of the hook and also the supporting surfaces for the clothes that are supported thereby. Thus the elastic metal band or strip 1 is bent, as at 2, to form the hook 3 having two relatively long leg portions 4 and 5. The end portion of the strip 1 that forms the leg 4 terminates in an outwardly bent curved portion 6, while the other leg 5 is shorter and terminates in a curved portion 7 that is located well above the bent portion 6. From the curved portion 7, the strip 1 extends outwardly from the hook 3, as at 8, and at the end of the portion 8 of the strip 1, the strip is bent to form a loop 9. The loop 9 terminates in a diagonally downwardly extending portion 10 which returns substantially to the plane extending between the legs 4 and 5. The portion 10 of the strip 1 terminates in a rela-

tively large circular portion 11 that is curved to form a relatively small curvature, preferably, so as to locate the outermost point of the curved portion 11 at a point well outside of the plane extending between the legs 4 and 5. The curved portion 11 terminates in a loop 12 which is located at the end of the strip 1.

When the strip 1 has been formed substantially as described and as illustrated in the drawings, the curved portion 6 is located at a point substantially midway between the curved portions 7 and 11. Also, the curved portion 6 is located in close proximity to the plane of the leg 5 which is tangential to the curved portion 11. Thus, when the hook 3 is placed over the edge of a body, such as a plate of glass, the body will be elastically engaged at the three points formed by the curved portions 6, 7, and 11, and the clothes hanger will thus be elastically secured in position.

The legs 4 and 5 of the hook 3 being relatively long locates the points of elastic engagement of the hook with the glass plate, such as the window of an automobile, on opposite sides of the glass plate and well below the edge of the window. Consequently, the points of support or engagement of the hook with the clothes that are hung thereon are well below the upper edge of the window. The loop 9 forms one of the hooks on which clothes may be hung and the curved portion 11 together with the loop 12 forms a lower hook on which clothes may be hung. There is thus provided, as is common in hooks for clothes, a hook for hanging a garment, such as the lower hook, and a hook for supporting a hat, such as the upper hook. Since the portion of the strip 1 that forms the lower hook, namely, the portion 11, is elastically pressed against the surface of the supporting object, such as the glass window of the automobile, and lies tangential thereto by reason of its curved form, a brim of a hat may easily be pushed between the curved portion 11 and the window and will be held in position by the elasticity of the strip 1. Thus a straw hat or a belt hat will be readily secured in position while the two clothes hooks of the clothes hanger may be used for supporting the other garments.

The hanger embodying my invention thus provides a convenient hook that may be readily placed in position or removed therefrom

and readily carried in a pocket and affords an exceedingly convenient means for supporting coats and hats in an automobile.

I claim:

- 5 In a clothes hanger, an elastic metal strip bent to form an elastic clamp having relative long legs located in proximity to each other and in substantially parallel arrangement, and a clothes hook portion formed of an outwardly and upwardly extending loop located 10 a short distance from the end of one of the legs of the clamp, and a downwardly inclined

portion that extends towards the other leg and terminates in an outwardly curved portion located below the said other leg, the said other leg terminating in an outwardly curved portion located intermediate the end of the first named leg and the outwardly curved portion of the said downwardly inclined portion.

15 20 In witness whereof I have hereunto signed my name to this specification.

FRANK S. SAXTON.
